UNITED STATES PATENT OFFICE.

AXEL C. V. MALM, OF DAYTON, OHIO, ASSIGNOR TO THE EGRY REGISTER COMPANY,
OF DAYTON, OHIO, A CORPORATION OF OHIO.

MANIFOLDING ATTACHMENT FOR TYPE-WRITERS.

1,178,660.

Specification of Letters Patent. Patented Apr. 11, 1916.

Application filed April 9, 1915. Serial No. 20,139.

To all whom it may concern:

Be it known that I, AXEL C. V. MALM, a citizen of the United States, residing at Dayton, in the county of Montgomery and State of Ohio, have invented certain new and useful Improvements in Manifolding Attachments for Type-Writers, of which the following is a specification, reference being had therein to the accompanying drawing.

This invention relates to manifolding attachments for typewriters, and more particularly to the means for supplying paper to such attachments. In attachments of this character the paper is supplied from rolls, the number of the rolls corresponding to the number of copies it is desired to make. These rolls are supported on a frame in the rear of the typewriter and the webs of paper are drawn from the rolls and passed about the platen in engagement with the paper-feeding devices of the typewriter, so that the webs of paper will be fed forward by the action of the line-spacing devices in the same manner that a sheet of paper is fed in the ordinary operation of the typewriter. The rolls may be very lightly mounted so that they will turn freely in their bearings, but, inasmuch as they come to a stop after each feeding operation, the inertia of the rolls, which is considerable, must be overcome by the paper-feeding devices, and this frequently causes the paper to slip or to feed forward unevenly, thus rendering the spacing uneven and throwing the several webs out of alinement. In some instances the frame which carries the paper rolls is in the form of a carriage and is caused to move with the typewriter carriage in order to keep the rolls in alinement with that carriage. In other cases it is desirable that the frame carrying the paper rolls should be fixed against movement. When such a fixed support is utilized the frame must be spaced far enough away from the typewriter to permit the paper carriage to move relatively to the paper rolls without tearing the paper. This is difficult to accomplish without putting the typewriter a considerable distance from the paper supply, and even then it is very difficult to hold the superimposed webs against lateral displacement relative one to the other, which displacement results in throwing the webs out

of alinement, and, as these webs of paper frequently carry printed forms, it is essential that perfect alinement should be maintained. Further, when the supply rolls are placed farther away from the typewriter carriage, the drag on the feeding mechanism is increased, and the liability of slipping becomes greater.

The object of the present invention is to provide means for overcoming both of these difficulties, and, to this end, a further object of the invention is to provide means for maintaining a loose supply of paper between the rolls and the feeding devices of the typewriter, so that these feeding devices will not have to overcome the inertia of the rolls, but will merely carry the weight of the slack in the webs between the feeding devices and the paper rolls; and, further, to provide means for preventing the relative lateral displacement of the superimposed webs as they are advanced by the feeding devices of the typewriter.

It is also an object of the invention to provide such a mechanism which will be very simple in its construction and operation and which will be under the direct control of the operator; and also to provide such a device which can be utilized with various kinds of supports for the paper rolls, and with these supports arranged in various positions.

In the accompanying drawings Figure 1 is a side elevation of a typewriter and paper roll support embodying my invention; Fig. 2 is a sectional detail view showing the actuating device for one of the paper rolls; Fig. 3 is a front elevation of the typewriter and fixed paper support, showing the former laterally displaced relatively to the latter; Fig. 4 is a perspective view of the paper guide; Fig. 5 is a sectional detail view of one of the paper rolls and its actuating devices; Fig. 6 is a side elevation of the paper roll support, showing the same applied to the edge of a table; Fig. 7 is a transverse sectional view of one of the paper rolls; and Fig. 8 is a longitudinal sectional view of the core of a paper roll, showing the supporting device therefor.

In these drawings I have illustrated one embodiment of my invention, and have shown this embodiment in connection with two different paper roll supports. It will

be understood, however, that this particular embodiment of the invention is chosen for the purpose of illustration only, and that the construction may be modified, and that the 5 invention, either in the form here illustrated or in a modified form, may be used with paper roll supports of various kinds. In this particular embodiment of the invention I have shown the same as applied to a typewriter 1, which may be of any suitable character, and may be mounted on a desk or table 2 of any suitable kind. As is common in typewriters this typewriter is provided with a platen 3 having means for operating 10 the same consisting of knurled knobs indicated at 3'. Coöoperating with this platen are the paper feeding devices or rolls 4. By the arrangement above set forth, when the platen 3 is rotated by means of the 15 knobs 3' the webs of paper 6 located between the paper rolls 7 and the typewriter will be fed through the typewriter. The feeding of the webs, it will be noticed, is entirely independent of the unwinding of the 20 paper from the rolls 7 which is done by an entirely separate and independent mechanism to be described hereinafter. The typewriter is here shown as provided with supplementary ribbon guides 5 which support 25 the ribbon in a plurality of folds, extending lengthwise of the platen and adapted to be interleaved between the webs of paper. This ribbon-supporting device does not constitute 30 a part of the present invention, but is fully shown, described and claimed in an application 35 for patent filed by Messrs. Malm and Rauh, Oct. 24th, 1914, Ser. No. 868,372. A plurality of webs of paper, of which there are, in the present instance, 4, as shown at 40 6, are mounted in the form of rolls 7 upon a supporting frame 8 which is arranged in the rear of and spaced some distance away from the typewriter. These webs of paper are, as has been stated, carried to the typewriter 45 and arranged to be advanced by the paper feeding devices thereof. In order that the several webs of paper may be held in their proper relative positions, and may not be laterally displaced by the movement 50 of the typewriter carriage, I have provided the latter with a paper guide 9. This guide comprises a bar 10 having at its ends attaching devices, such as arms 11, by means of which it may be rigidly secured to the typewriter carriage. In the present instance it 55 is secured to the opposite end members of the ribbon support. This bar is provided at its ends with recesses to receive the edges of several webs of paper. These recesses 60 are here shown as formed by inwardly extending flanges 12 secured to the plate near the ends thereof and spaced away from the plate a distance sufficient to receive the several webs of paper in their superimposed 65 relation. The space between the bases of

the recesses at the ends of the bar 10 is approximately equal to the widths of the webs of paper which are being fed to the machine. Consequently, when the webs have been placed in the guide, by placing 70 the edges thereof under the flanges 12, they will be maintained in substantially vertical alinement and all lateral displacement thereof effectually prevented. Preferably, the bases of the grooves are rounded, as 75 shown at 13, so that there will be no corners or projecting edges to engage the edges of the paper.

In that form of the devices shown in Figs. 1 and 3, the paper roll supporting frame 8 is adapted to be mounted on a wall or other vertical support, as shown at 14, and comprises forwardly extending frame members in which are journaled a plurality of shafts 15 adapted to have mounted thereon the hollow cores 16 on which the webs of paper are rolled. Usually the shaft is provided with a drum 17 which fits snugly within the core 16, but this, of course, depends upon the size of the core which is to be 90 used. Suitable means are provided for preventing the rotation of the core and the paper roll on the drum, and, in the present instance, this means comprises a flat spring 18 rigidly secured to the drum and arranged 95 in a recess 19 so that its lateral edges will project slightly beyond the cylindrical surface of the drum and bite into the interior surface of the core 16, as shown in Figs. 7 and 8.

As has been explained, the weight of the paper and the inertia of the paper rolls impose a drag on the paper-feeding devices of the typewriter, which is objectionable, and, to overcome this drag, I have provided 100 means independent of the paper-feeding devices for withdrawing the paper from the paper rolls and maintaining a slack portion in the webs between the paper rolls and the typewriter feeding devices. This means is 105 preferably of such a character that it can be operated by the typewriter operator to positively unwind webs of paper from the rolls. As here shown, one end of each shaft 15 is provided with a ratchet wheel 20 which is 110 rigidly secured thereto and is adapted to be engaged by a pawl 21 carried by a slide bar 22. In the present form of the device the paper-supporting frame is so arranged as to support the rolls with their axes in vertical 115 alinement, and the single actuating bar 22 carries the pawls 21 for actuating each of the ratchet wheels. The pawls 21 are pressed forward by springs 23 and are so arranged that on the upward movement of 120 the slide bar they will engage the ratchet wheels and move the paper rolls in a direction to unwind the paper therefrom. On the return movement of the slide bar the pawls will ride over the ratchet teeth with- 125

out interfering with the rotation of the rolls, thus a quick movement of the slide bar will impart rotation to the rolls which will continue some time after the 5 slide bar and pawls have completed their movement, thus permitting a very considerable amount of paper to be unwound by a single movement of the slide bar. The slide bar may be actuated in any suitable manner, but, as has been stated, its operation is 10 preferably under the control of the operator, and to this end I have connected the lower end of the slide bar, by means of a link 24, with one end of a lever 25, which is pivotally mounted between its ends on a 15 bracket 26 secured to the floor beneath the typewriter desk, and is further provided at that end opposite the end connected with the link 24 with a treadle or footpiece 27. 20 This arrangement is such that the operator may, at intervals during the operation of the typewriter, press the lever 25 with his foot and cause a quantity of paper to be unwound from the rolls. An occasional operation 25 of the device will be sufficient to provide ample slack in the web, and this slack enables the paper to be easily advanced by the feeding devices, as the operation of these devices is resisted only by the 30 weight of the slack in the paper.

It is sometimes preferable to support the paper rolls in some other manner than on a wall or the like, and, in Fig. 6, I have shown a roll-supporting frame adapted to be 35 clamped to the edge of a desk or table. As there shown, this frame comprises vertical side members 28, similar to the frame 8, and is provided at its upper end with a clamp 29, by means of which it may be fastened to the rear edge of the typewriter 40 desk and allowed to depend beneath the top of the desk. The manner of supporting the rolls and unwinding the paper therefrom is the same in this instance as in that above 45 described, but the webs of paper, which are shown at 30, are carried beneath the frame 28 and over a guide bar or roller 31, supported by the upper portion of the frame and arranged above the uppermost part 50 thereof so that the paper may pass from this bar to the typewriter without interference.

As has been stated, the rolls will continue to move after the pawls have returned to their normal positions, and I prefer to provide 55 some means to cause the rolls to move substantially equal distances so that approximately the same amount of paper will be unwound from each roll. This may be accomplished in various ways, but, preferably, I establish connections between the adjacent rolls, and, in the present instance, these connections comprise small belts 32 which may be formed of rubber bands or the like and which extend about the reduced 60 portions of knobs 33 which are secured to

the outer ends of the shafts adjacent to the ratchet wheels. Preferably, these knobs have their inner portions grooved, as shown at 34, to form guides for the belts.

The operation of the device will be readily understood from the foregoing description, and it will be apparent that I have provided means whereby webs of paper may be fed from supply rolls by the ordinary paper-feeding devices of the typewriter without imposing such a strain on those devices as to prevent the proper feeding of the paper, and, further, that the several webs of paper will be maintained in their proper superimposed positions during 70 the feeding and writing operations.

While I have shown and described one embodiment of my invention, I wish it to be understood that I do not desire to be limited to the details shown and described, as various modifications will occur to a person skilled in the art.

Having thus fully described my invention, what I claim as new and desire to secure by Letters Patent, is:—

1. The combination, with a typewriter having a paper feeding device, means for operating the said feeding device, a support mounted in fixed relation to said feeding device and independently thereof, and a roll 95 of paper mounted on said support and having its web arranged to be advanced by said feeding device, of means operable independently of said first means and of the typewriter for unwinding the web from said roll 100 and maintaining the portion of the web which is between the roll and the feeding device in a slack condition which will offer little resistance to the operation of the feeding device.

2. The combination, with a typewriter having a paper feeding device, means for operating the said feeding device, a support mounted in fixed relation to said feeding device and independently thereof, and a plurality of rolls of paper mounted on said support and having their webs arranged to be advanced by said feeding device, of means operable independently of said first means and of the typewriter for simultaneously unwinding the webs from said rolls and maintaining the portions of said webs which are between the rolls and the feeding device in a slack condition which will offer little resistance to the operation of the feeding device.

3. The combination with a typewriter having a paper-feeding device mounted for longitudinal movement relatively to said typewriter, means for operating said feeding device, a paper support fixed with relation to said feeding device and a plurality of rolls of paper mounted on said support and having their webs arranged in superimposed relation to be simultaneously advanced by 125 130

- 4 said feeding device, of independently mounted means to unwind the webs from their rolls, and a guide bar connected with said feeding device for longitudinal movement in unison therewith, and having recesses at its opposite ends to receive the respective edges of said superimposed webs to guide the same and prevent relative lateral displacement thereof.
- 10 4. The combination, with a typewriter having a paper feeding device capable of movement relatively to said typewriter, a paper support and a plurality of rolls of paper mounted on said support and having their webs arranged in superimposed relation to be simultaneously advanced by said feeding device, of a guide connected with and movable in unison with said feeding device, said guide comprising a flat plate having U-shaped ends adapted to engage the edges and tops of said superimposed webs to hold the same in proper position.
- 15 5. The combination, with a typewriter having a paper feeding device capable of movement relatively to said typewriter, a paper support and a plurality of rolls of paper mounted on said support and having their webs arranged in superimposed relation to be simultaneously advanced by said feeding device, of a flat guide bar connected with said feeding device for movement in unison therewith and having U-shaped ends arranged to engage the edges and top of said superimposed webs to properly guide
- 20 30 35 6. The combination with a typewriter having a paper-feeding device and a plurality of rolls of paper mounted in fixed relation to said typewriter, of a ratchet wheel connected with each of said rolls of paper, an actuating bar, a plurality of pawls carried by said actuating bar and arranged to engage the respective ratchet wheels, and means under the control of the operator for operating said actuating bar.
- 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925
2. The combination with a typewriter having a paper-feeding device and a plurality of rolls of paper having their webs arranged in superimposed relation to be simultaneously advanced by said feeding device, of an actuating bar movably mounted adjacent to said rolls of paper and means for establishing operative connections between said bar and the respective rolls to cause the latter to be rotated, a lever mounted adjacent to said typewriter and an operative connection between said lever and said actuating bar.
3. The combination with a typewriter having a paper-feeding device and a paper-supporting frame having a plurality of rolls of paper mounted thereon, a bar slidably mounted on said frame and means actuated by the movement of said bar to impart rotary movement to the several rolls of paper, and means under the control of the operator for actuating said slide bar.
4. The combination with a typewriter having a paper-feeding device, a paper-supporting frame having a plurality of rolls of paper mounted thereon, a bar slidably mounted on said frame and means actuated by the movement of said bar to impart rotary movement to the several rolls of paper, means under the control of the operator for actuating said slide bar, and means for causing the several rolls of paper to be moved substantially equal distances.
5. The combination with a typewriter having a paper-feeding device, a paper-supporting frame having a plurality of rolls of paper mounted thereon, a bar slidably mounted on said frame and means actuated by the movement of said bar to impart rotary movement to the several rolls of paper, means under the control of the operator for actuating said slide bar, and means for causing the several rolls of paper to be moved substantially equal distances.
6. The combination with a typewriter having a paper-feeding device, means for operating said feeding device, and a plurality of rolls of paper mounted adjacent to said typewriter and having their webs arranged in superimposed relation to be simultaneously advanced by said feeding device, of means adjacent the typewriter and independent of the means for operating said feeding device, said means adjacent the typewriter being connected directly to the rolls, and means for causing the several rolls to be rotated substantially equal distances.
7. The combination with a typewriter having a paper-feeding device and a plurality of rolls of paper mounted in fixed relation to said typewriter, of a ratchet wheel connected with each of said rolls of paper, an actuating bar, a plurality of pawls carried by said actuating bar and arranged to engage the respective ratchet wheels, a lever arranged to be actuated by the operator and an operative connection between said lever and said actuating bar.
8. The combination with a typewriter having a paper-feeding device and a plurality of rolls of paper mounted in fixed relation to said typewriter, of a ratchet wheel connected with each of said rolls of paper, an actuating bar, a plurality of pawls carried by said actuating bar and arranged to

engage the respective ratchet wheels, a lever pivotally mounted beneath said typewriter, having one end arranged to be actuated by the operator and a connection between said lever and said actuating bar.

9. The combination with a typewriter having a paper-feeding device and a plurality of rolls of paper having their webs arranged in superimposed relation to be simultaneously advanced by said feeding device, of an actuating bar movably mounted adjacent to said rolls of paper and means for establishing operative connections between said bar and the respective rolls to cause the latter to be rotated, a lever mounted adjacent to said typewriter and an operative connection between said lever and said actuating bar.

10. The combination with a typewriter having a paper-feeding device, a paper-supporting frame having a plurality of rolls of paper mounted thereon, a bar slidably mounted on said frame and means actuated by the movement of said bar to impart rotary movement to the several rolls of paper, and means under the control of the operator for actuating said slide bar.

11. The combination with a typewriter having a paper-feeding device, a paper-supporting frame having a plurality of rolls of paper mounted thereon, a bar slidably mounted on said frame and means actuated by the movement of said bar to impart rotary movement to the several rolls of paper, means under the control of the operator for actuating said slide bar, and means for causing the several rolls of paper to be moved substantially equal distances.

12. The combination with a typewriter having a paper-feeding device, means for operating said feeding device, and a plurality of rolls of paper mounted adjacent to said typewriter and having their webs arranged in superimposed relation to be simultaneously advanced by said feeding device, of means adjacent the typewriter and independent of the means for operating said feeding device, said means adjacent the typewriter being connected directly to the rolls, and means for causing the several rolls to be rotated substantially equal distances.

13. The combination with a typewriter having a paper-feeding device and a plurality of rolls of paper mounted adjacent to said typewriter and having their webs arranged in superimposed relation to be simultaneously advanced by said feeding device, of means under the control of the operator for imparting movement to said rolls of paper to unwind the webs therefrom, and means, other than the means for imparting movement to said rolls, for connecting the several rolls one to the other to cause them to rotate in unison and for substantially equal distances.

14. The combination with a typewriter having a paper-feeding device and a plurality of rolls of paper mounted adjacent to said typewriter and having their webs arranged in superimposed relation to be simultaneously advanced by said feeding device, of means under the control of the operator for imparting movement to said rolls of paper to unwind the webs therefrom, and belts connecting the adjacent rolls to cause them to rotate in unison.
15. The combination, with a typewriter having a paper feeding device, of a plurality of rolls for paper mounted in fixed relation to said typewriter, operating means mounted on each roll, and means coöperating with said operating means to simultaneously feed the paper from said rolls.
16. The combination, with a typewriter having a paper feeding device, of a plurality of rolls for paper mounted in fixed relation to said typewriter, operating means

mounted upon each roll, means coöperating with said operating means to feed the paper from said rolls, and means connecting the several rolls together to cause them to rotate in unison.

17. The combination, with a typewriter having a paper feeding device, means for operating the same, and a roll of paper having its web arranged to be advanced by said feeding device, of an actuating device connected to said roll and arranged to impart positive movement to said roll of paper to unwind the same, and means for operating said actuating device independently of said first-mentioned means.

In testimony whereof, I affix my signature in presence of two witnesses.

AXEL C. V. MALM.
